UNITED STATES PATENT OFFICE.

CHARLES T. BLOOMER, OF NEWARK, NEW YORK.

PAPER VESSEL.

1,053,561.

Specification of Letters Patent. Patented Feb. 18, 1913.

Application filed August 11, 1911. Serial No. 643,570.

To all whom it may concern:

Be it known that I, CHARLES T. BLOOMER, a citizen of the United States, residing at Newark, in the county of Wayne and State 5 of New York, have invented a new and useful Paper Vessel, of which the following is a specification.

This invention relates to paper vessels and particularly to means for closure 10 thereof.

The object of this invention is to provide means for effecting a simple and convenient means for closing and sealing vessels of this character which are provided with suitable 15 cover flaps to retain the contents therein.

With the above and other objects in view this invention is embodied in the novel arrangement and construction hereinafter described and as illustrated in the accompanying drawings, in which similar reference 20 characters indicate similar parts, and in which,—

Figure 1 is a perspective of the vessel when closed. Fig. 2 is a perspective thereof 25 when open.

Referring specifically to the drawings, 5 indicates the vessel of usual construction, being folded from a suitable paper blank and having the folded sides 6 and 6' over- 30 lapping each other at the upper edge of the vessel, the inner cover flaps 13, and the outer cover flaps 12 and 14, the latter flap 14 being at the side on which the folded sides 6 and 6' lie and the flap 12 being arranged at 35 the opposite side.

A metallic tongue 7 projects upward from behind the folded sides 6 and 6' being set 40 slightly to one side of the center of the vessel and a tab 9 extends from the outer edge of the flap 12 and has an aperture 10 therein, the outer edge 10^a of which is adapted to 45 coincide with the upper edges of the folded sides 6 and 6' when the flap 12 is folded down in position as shown in Fig. 1, the tongue 7 passing through the aperture 10 and when folded back over the outer faces 50 of the sides 6 and 6' with the tab 9 thereunder seals the flap 12 in position. The outer edge of the tab 9 is cut diagonally as 55 indicated at 9^a to fit along the diagonal edge of the side 6 and the inner edge 9^b is arranged at the center of the vessel in the path of the bail 11 which is secured to the folded sides 6 and 6' in the usual manner (not 60 shown).

In closing the vessel, the flaps 13 are first

folded inward over the top thereof and the flap 14 is then folded downwardly thereover and finally the flap 12 is folded down over the flap 14, the tongue 7 passing conveniently through the aperture 10. Then by bending the tongue 7 downward the flap 12 is conveniently sealed in its position. The edge 10^a of the aperture 10 coinciding with the upper edges of the folded sides 6 and 6' provides for a secure connection between the tongue 7 and the tab 9. The tab 9 is readily released from the tongue 7 by pressing the corresponding side of the vessel slightly inward which permits the fingers 70 to engage the tab and then by bending the same upward the tab is permitted to slide off of the tongue to allow the flaps to open.

The chief feature of this invention in connection with the general type of vessel as 75 described, is the provision of the apertured tab 9 projecting from the free edge of the cover flap 12 and in the same plane with the said flap and the metallic tongue 7 80 standing from behind the folded sides and perpendicular to the "cover plane" of the vessel, whereby upon the cover flaps being folded over the vessel the said tongue passes readily through the apertured tab to be bent over the respective side of the vessel to 85 clamp the tab against the said side of the vessel. The tongue 7 in being secured between the said folded side and the corresponding side of the vessel prevents the tongue from being loosened in the act of 90 bending the tongue and otherwise prevents the tongue from becoming loosened. The tab 9 in being folded over the side of the vessel eliminates the greater part of the strain from the tongue 7 thus reducing the 95 tendency of the tab from tearing loose. It will also be noted that the sides of the vessel in becoming bulged when the vessel is filled, and upon the cover flaps being folded over the vessel, the tongue 7 may be readily bent 100 to pass through the aperture 10 in the tab 9, and then by drawing the free end of the tongue away from the corresponding side of the vessel the cover flap 12 is drawn taut over the vessel, the said tongue and tab then 105 being bent over the corresponding side of the vessel to clamp the tab against the said side.

What is claimed as new is:—

1. A vessel of the character described, provided with a cover flap on one side provided with an apertured tab projecting from

the free edge thereof and in the same plane with the said flap, and a metallic tongue upstanding from the opposite side perpendicular to the cover plane and adapted to 5 pass through the apertured tab upon the cover flap being folded over the vessel and to be bent over the respective side of the vessel to clamp the tab against the said side of the vessel.

- 10 2. A receptacle folded from a blank and having a bottom, sides, ends, corner folds overlapping the sides and also overlapping each other, a bail connected with said overlapping corner folds, at the middle of the 15 sides, inner flaps hinge-connected with the ends, and inner and outer cover flaps hinge-connected with the sides, the outer cover flap having, offset from the middle thereof, a tab formed with an opening, a bendable fastening member extending upward from the side with which the inner cover flap is hinge-connected and being adapted to extend through the opening in said tab and to be folded with said tab downward on the out- 20 side of said corner folds.
- 25 3. A receptacle folded from a blank, and having a bottom, sides, ends, corner folds overlapping the sides, and also overlapping

each other, a bail connected with said overlapping corner folds at the center of the 30 sides, inner flaps hinge-connected with the ends, and inner and outer cover flaps hinge-connected with the sides, the outer cover flap having, offset from the middle thereof, an integral tab formed with an opening, one 35 corner of said outer cover flap and of said tab being cut away diagonally in line with each other, a bendable fastening member extending upward from the side with which the inner cover flap is hinge-connected, said 40 fastening strip being offset to one side of said bail and being adapted to extend through the opening in said tab and to be folded with said tab downward on the outside of said corner folds, so that the diagonally cut edge of said tab will lie parallel with the adjacent diagonally extending edge of the outer corner fold.

In testimony that I claim the foregoing as my own, I have hereto affixed my signature in the presence of two witnesses.

CHARLES T. BLOOMER.
